SLEEVE ASSEMBLING APPARATUS FOR
LITHOGRAPHIC ROLLSNorman A. Mack, Riverside, Ill., assignor to
Roberts & Porter, Inc., Chicago, Ill., a corpora-
tion of Illinois

Application March 13, 1946, Serial No. 654,205

16 Claims. (Cl. 101—1)

1

This invention relates to new and useful improvements in outer jackets for moistening and inking rollers of lithographic printing machines and the like and also to apparatus for applying such jackets, in tubular form, to such rollers.

The present invention constitutes an improvement over the construction disclosed in my co-pending application Serial No. 611,339, filed August 18, 1945, for the same subject.

The apparatus disclosed in the aforesaid application relates to a machine for re-sleeving lithograph rolls with a material such as "Molleton," which machine is manually operated. The present invention relates to a power operated machine for the same purpose which differs in constructional details from the manually operated machine and is easier to operate and faster than the former machine.

The general practice which has been extensively used in jacketing rollers of the character above referred to, consists in sewing around the roller a piece of relatively resilient, comparatively thick fabric material having liquid absorbent characteristics. One of the fabric materials which has been extensively used is termed "Molleton," the thickness of which is in excess of $\frac{1}{8}$ inch and which in general has been found very satisfactory for distributing liquid evenly and uniformly over the plate. The jacketing material is sewed around the roller along the longitudinal abutting marginal edges thereof, and each of the overhanging end portions of the material has a draw-cord stitched to the marginal edges thereof, by over-hand stitching, so that the cords may be drawn taut to form the overhanging portions of the jacket snugly around the end portions of the roller and in surrounding relation to the projecting shaft portions of the roller. The ends of the cords are then tied firmly together.

Such coverings are removed from the rollers, after they are soiled by ink and moistening fluid, by severing the stitching and scraping them off the roller. The matter of renewing outer jackets of such rollers is extremely time consuming, and it usually requires three to four hours to sew a fresh jacket or covering onto a roller of average length.

Rollers for lithographing machines generally range from 2 inches to $3\frac{3}{4}$ inches in diameter and from $10\frac{1}{2}$ inches to 79 inches in length. Such rollers usually include a central core or shaft of metal surrounded by a body of resilient material, such as rubber. The rubber body is usually covered by one or more intermediate layers of suitable resilient material such as flannel, knitted

2

wool or cotton, and around which the outer covering or jacket of absorbent material is stitched.

It is an object of the present invention to provide an improved power operated machine for quickly applying a jacket to rollers of lithographing machines with a minimum of hand operations.

One of the objects of this invention is to provide an improved tubular outer jacket and novel apparatus for applying said jacket to rollers of lithographing machines in a manner so as to result in a saving of several hours' time as compared to present day conventional methods of producing and applying outer jackets to such rollers.

15 Another object is to provide a novel apparatus for applying a preformed tubular outer jacket to rollers of lithograph printing machines in a few minutes' time.

A further object is to provide novel apparatus 20 for quickly and easily applying a preformed tubular outer jacket to a roller of a lithograph printing machine and wherein said apparatus may be quickly and easily adjusted for performing a jacketing operation on rollers of various lengths.

25 Still another object is to provide novel apparatus for mechanically jacketing a roller of a lithograph printing machine and wherein said apparatus is relatively simple in construction, durable and efficient in operation, and capable of 30 being economically manufactured.

A still further object is to provide a novel, preformed tubular outer jacket for rollers of lithograph printing machines having means at one end thereof for quickly and easily constricting 35 the end portion of the tubular jacket to form a transverse shoulder for snugly fitting against the end portion of the roller in surrounding relation to the metallic projecting end portions of the core or shaft of the roller.

40 It is still another object of the invention to provide a power operated machine for the purpose described, wherein the jacket, which has been applied to a mandrel, is forced over the roller and the mandrel thereupon readily removed from the 45 roller.

It is also an object of the invention to provide a power operated machine of simple and sturdy construction for the purpose described.

With these and other objects in view, my invention consists in the construction, arrangement and combination of the various parts of my device whereby the objects contemplated are attained as hereinafter more fully set forth, pointed out in my claims, and illustrated in the accompanying drawings, in which:

Figure 1 is a side elevational view of the novel apparatus and the novel form of tubular jacket embodying the present invention, with a roller and jacket shown positioned preparatory to insertion into the apparatus for performing a jacking operation thereon, the dotted lines showing the jacket partially applied to the roller;

Figure 2 is a view similar to Figure 1 and showing the roller and the apparatus in a position at which the roller has been telescoped into the jacket; the dotted lines show the mandrel removed;

Figure 3 is a front elevational view of the apparatus shown in Figures 1 and 2;

Figure 4 is a partial vertical sectional view of the apparatus taken on line 4—4 of Figure 3;

Figure 5 is a transverse sectional view of the apparatus taken on line 5—5 of Figure 4;

Figure 6 is a partial vertical sectional view taken on line 6—6 of Figure 2; and

Figure 7 is a fragmentary view of one end of the jacket.

Referring now to the drawings for a detailed description of the invention, numeral 11 designates generally a frame structure for the machine and includes a base 12, an upright angle member 13 secured thereto, an upper platform 14 supported by the angle member 13 and suitable upper and lower brackets 15 and 16 for bracing the platform 14 and the angle member 12.

A driving motor 17 and a suitable gear box 18 are mounted on the platform 14. The motor 17 drives reversible gears (not shown) in the gear box 18 through a shaft and coupling 19, and the gears rotate a worm or threaded screw 21. The worm 21 extends vertically the full height of the machine and has its upper end journalled in a bearing 22 in the platform 14 and its lower end journalled in a bearing 23 in the base 12.

As best shown in Figures 4, 5 and 6, a traveling bracket generally indicated at 24 is threaded on the worm 21 by a threaded boss 25 in a back plate 30. A flat platform 26 is formed integrally with the back plate 30 and is provided with a relatively large central aperture 27. The bracket 24 is provided with slots 28 which engage sides 29 of the angle piece 13 and the bracket is thus guided and prevented from swinging about the worm 21. Bracing members 31 extend forwardly from the back plate 30 to the platform 26. A vertical guiding tube 32 is threaded into a boss 33 on the base 12 for a purpose hereinafter described.

When it is necessary to renew soiled outer jackets of rollers of lithograph machines, said outer jackets are cut off the roller in a customary manner, as by means of a knife. A jacket 34, which is to constitute the outer cover for a roller, indicated at 35, is preformed as a tube and when made of materials such as "Molleton," the abutting marginal longitudinal edges are stitched together at 35^a, preferably on a sewing machine and the tubular jacket 34 is internally dimensioned to insure a tight fit on the roller 35.

The roller 35 is of usual construction, including a central metallic core 36, surrounded by a body of resilient material 37, such as rubber, the latter being incased in one or more coverings 38 of suitable material, such as flannel and/or knitted wool or cotton. Projecting end portions 39 of the core of the roller are of suitable length and diameter for mounting in the bearings of a lithographing machine.

Rollers for lithographing machines, as stated, vary in length and also in bearing diameter, and

the present machine is adapted to handle quite a variety of roller sizes, as will appear as the description proceeds.

The tubular jacket 34 is of a length to provide overhanging end portions when it surrounds the roller and at least one end portion, as best shown in Figure 7, is provided with a multiplicity of circumferentially spaced apart metallic eyelets 41, through which is threaded a suitable draw-string or cord 42. The eyelets serve to firmly grip the fabric between the shoulders thereof and provide a strong durable fastening on which substantial strain may be imposed without tearing the fabric. The eyelets may be formed in the end portion of the jacket, either prior to the forming of the material as a tube, or after it is formed. Preferably, the other end of the tube 34 is sewn by hand after it is applied to the roller 35, but this end may also be provided with eyelets and a draw-string, if desired.

When the roller 35 is to be covered with a new tubular jacket 34, the draw-string 42 is drawn together to form a transverse stop shoulder as indicated at 43, against which the end of a mandrel, generally indicated at 44, is adapted to abut when the tube 34 is placed thereon, as shown in Figures 1 to 3. When the tube 34 is on the roller 35, the shoulder 43 abuts one end of the roller 35 with the stub of the bearing shaft 39 extending therethrough. By utilizing the eyelets and draw-string, I have found that about one hour in time is saved which would ordinarily be required in sewing the end of the jacket in the manner heretofore practiced.

The mandrel 44 comprises an elongated body of bifurcated form, providing a pair of elongated resilient fingers 45 of circular contour in cross section. The fingers 45 are formed as sheet metal stampings and have lower ends bent to form transversely extending flanges 46, which flanges are firmly gripped between a pair of annular metallic rings 47 and 48 held together by screws 49. The rings 47 and 48 together with the flanges 46 constitute a head adapted to be engaged by the platform 26 of the movable bracket 24, with the body of the mandrel projecting through the aperture 27 in the platform 26. The aperture 27 is large enough to accommodate a large number of different size rollers.

The jacket 34 of "Molleton" is first applied to the mandrel 44, the mandrel being of such a size that it fits the interior of the jacket 34 very snugly and also of such a size that the resilient fingers 45 expand slightly when the mandrel is forced over the roller 35. Therefore, when the relatively thin mandrel 44 is withdrawn from the jacket 34, the jacket grips the roller with a very snug fit.

After the jacket 34 is forced on the mandrel 44 so that the ends of the mandrel fingers 45 are adjacent the shoulder 43 of the jacket, which has been formed by drawing on the drawstring 42, the jacket and mandrel are placed on the machine in the position shown in Figure 1 and the bracket 24 is run downwardly by operating the motor 17 and screw 21 through a conventional reversing switch 51 until the bottom of the platform 26 engages the ring 47. The roller 35 has its lower extension 39 disposed in a socket 52 in the upper end of the guide member 32, which socket is large enough to accommodate roller extensions of different sizes. The roller 35 is then guided by hand until the jacket 34 is forced over the end thereof by operating motor 17 to run bracket 24 downwardly.

The bracket 24 continues to travel downwardly until the jacket and mandrel are forced completely over the roller 35 and the shoulder 43 of the jacket 34 abuts against an upper shoulder 53 of the roller 35. The upper stub shaft 39 then extends out of the jacket 34, as shown in Figure 2. The bracket 24 continues to travel downwardly on screw 21, thus withdrawing the mandrel 44 from the jacket 34 and roller 35, thus leaving the jacket 34 snugly fitting the roller 35. The bracket 24 is shown in its lowermost position in dotted lines in Figure 2, but ordinarily it is not necessary to run the bracket 24 down this far, as the mandrel 44 falls down by gravity before the bracket 24 reaches the bottom of its travel. After the mandrel 44 falls out, the covered roller is removed from the machine and the drawstring 42 is drawn tight about its stud 39. Preferably, the other end of the jacket 34 is hand sewn closely around its stud 39.

The bracket is then run upwardly on worm 21 by operating the main reversing switch 51 which reverses the rotation of motor 17 and worm 21 in any well known manner. Limit switches 54 and 55 are provided at the upper and lower ends of the machine and are provided with switch arms 56 and 57 which are contacted and moved by bracket 24 if it travels to the extremity of worm 21 to cut off the motor and stop rotation of the worm. This provides a safety measure to prevent damage to the machine if the operator fails to stop the motor in time with the main switch 51.

While I have herein referred to "Molleton" as the material for providing outer jackets for the rollers, manifestly other materials may be satisfactorily employed, and may be made up as endless tubing cut to desired lengths. In such cases, the eyeletting operation may still be satisfactory, employed with the attendant advantages above indicated.

From the foregoing, it will be apparent that I have provided an improved power operated machine for re-sleeving lithograph rollers which effects considerable saving in time over old methods and which is inexpensive to build and easy to operate. Furthermore, the machine is adapted to re-sleeve a large number of different size rollers, it being obvious that a roller of the largest size is illustrated in the drawings.

Although I have herein shown and described certain preferred embodiments of my invention, manifestly it is capable of modification and rearrangement of parts without departing from the spirit and scope thereof. I do not, therefore, wish to be understood as limiting this invention to the precise forms herein disclosed, except as I may be so limited by the appended claims.

I claim as my invention:

1. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for supporting the roller, movable means for engaging the mandrel after the sleeve has been applied thereto, and reversible power operated means for moving said engaging means to telescope the mandrel and sleeve over the roller and to strip the mandrel therefrom.

2. Apparatus for mechanically jacketing a roller of a lithograph printing machine with a

tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, a movable bracket for moving said mandrel and sleeve after the sleeve has been applied to said mandrel, said bracket adapted to force the mandrel and sleeve over the fixedly supported roller and then to strip said mandrel therefrom, and reversible power operated means for moving said bracket first to perform the jacketing operation and then to a position for initiating another jacketing operation.

3. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, and reversible power operated means for moving said movable means first to perform a complete jacketing operation and then to a position for initiating another jacketing operation.

4. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, and reversible power operated means for moving said movable means first to perform a complete jacketing operation and then to a position for initiating another jacketing operation, said power operated means including a motor, a reversible screw driven by said motor and cooperating threads for said screw on said movable means.

5. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, and reversible power operated means for moving said movable means first to perform a complete jacketing operation and then to a position for initiating another jacketing operation, said power operated means including a motor, a reversible screw driven by said motor and cooperating threads for said screw on said movable means, said motor being reversible to reverse the rotation of said screw and the direction of travel of said movable means.

6. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, reversible power operated means for moving said movable means first to perform a complete jacketing operation and then to a position for initiating another jacketing operation, said power operated means including a motor, a reversible screw driven by said motor and cooperating threads for said screw on said movable means, said motor being reversible to reverse the rotation of said screw and the direction of travel of said movable means, and limit switches for deenergizing said motor to limit the travel of said movable means.

7. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, reversible power operated means for moving said movable means first to perform a complete jacketing operation and then to a position for initiating another jacketing operation, said power operated means including a motor, a reversible screw driven by said motor and cooperating threads for said screw on said movable means, and means for preventing rotation of said movable means about said screw.

8. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for supporting said roller comprising a guide shaft fixedly secured to said apparatus in a position to engage one end of the roller, movable means for moving the mandrel and sleeve after the sleeve has been applied to said mandrel, said movable means adapted to force the mandrel and sleeve over said fixedly supported roller and then to strip said mandrel therefrom and telescope it over said guide shaft.

9. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for supporting said roller comprising a guide shaft fixedly secured to said apparatus in a position to engage one end of the roller, movable means

for moving the mandrel and sleeve after the sleeve has been applied to said mandrel, said movable means adapted to force the mandrel and sleeve over said fixedly supported roller and then to strip said mandrel therefrom and telescope it over said guide shaft, and reversible power operated means for moving said movable means first to perform a jacketing operation and then to a position for initiating another jacketing operation.

10. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, a base plate, an upright secured to said base plate, a platform secured to the upper end of the upright, a motor mounted on said platform, a reversible screw driven by said motor and journalled in the base plate and the platform, means for fixedly supporting the roller comprising a guide shaft secured to said base plate, a movable bracket having threads cooperating with said screw to move the bracket up and down between said platform and base plate, said bracket adapted to force the mandrel and sleeve over the fixedly supported roller and then to strip said mandrel therefrom, and means for reversing the rotation of screw for moving said bracket first to perform a jacketing operation and then to a position for initiating another bracketing operation.

11. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, a base plate, an upright secured to said base plate, a platform secured to the upper end of the upright, a motor mounted on said platform, a reversible screw driven by said motor and journalled in the base plate and the platform, means for fixedly supporting the roller comprising a guide shaft secured to said base plate, a movable bracket having threads cooperating with said screw to move the bracket up and down between said platform and base plate, said bracket adapted to force the mandrel and sleeve over the fixedly supported roller and then to strip said mandrel therefrom, and means for reversing the rotation of screw for moving said bracket first to perform a jacketing operation and then to a position for initiating another bracketing operation, said upright comprising a U-shaped angle member including a pair of side arms, said arms cooperating with said bracket to prevent rotation thereof about said screw.

12. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, a base plate, an upright secured to said base plate, a platform secured to the upper end of the upright, a motor mounted on said platform, a reversible screw driven by said motor and journalled in the base plate and the platform, means for fixedly supporting the roller comprising a guide shaft se-

cured to said base plate, a movable bracket having threads cooperating with said screw to move the bracket up and down between said platform and base plate, said bracket adapted to force the mandrel and sleeve over the fixedly supported roller and then to strip said mandrel therefrom, and means for reversing the rotation of screw for moving said bracket first to perform a jacketing operation and then to a position for initiating another bracketing operation, said upright comprising a U-shaped angle member including a pair of side arms, said bracket having slots therein for receiving said side arms to provide guides for said bracket and to prevent rotation thereof about said screw.

13. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, a base plate, an upright secured to the base plate, a motor for said apparatus, a reversible screw driven by said motor, means for fixedly supporting the roller on said apparatus, a movable bracket having threads cooperating with said screw to move the bracket up and down between said platform and base plate, said bracket adapted to force the mandrel and sleeve over the fixedly supported roller and then to strip said mandrel therefrom, and means for reversing the rotation of screw for moving said bracket first to perform a jacketing operation and then to a position for initiating another bracketing operation.

14. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, an angle member, end plates secured to the angle member, a reversible screw journaled in said end plates, means for fixedly supporting the roller comprising a guide shaft secured to one of said end plates, a movable

- bracket having thread cooperating with said screw to move the bracket along the screw, said bracket adapted to force the mandrel and sleeve over the fixedly supported roller and then to strip said mandrel therefrom, and means for reversing the rotation of screw for moving said bracket first to perform a jacketing operation and then to a position for initiating another bracketing operation.
15. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, movable means for moving said mandrel and sleeve after the sleeve has been applied to said mandrel, said movable means adapted to force the mandrel and sleeve over said roller and then to strip the mandrel therefrom, and reversible power operated means for moving said movable means first to perform a complete jacketing operation and then to a position for initiating another jacketing operation, a relatively rigid shoulder provided at one end of said sleeve, said shoulder engaging one end of the roller when the sleeve and mandrel are fully telescoped thereon and preventing further movement of said sleeve by said movable means.
16. Apparatus for mechanically jacketing a roller of a lithograph printing machine with a tubular sleeve of absorbent fabric comprising a hollow mandrel dimensioned internally for snugly fitting telescopically a roller to be jacketed, and dimensioned externally for a snug fit thereon of the major portion of the length of a tubular sleeve of absorbent fabric, means for fixedly supporting said roller, a movable bracket having an extension thereon, a stiffening flange at one end of said mandrel, said extension adapted to engage said stiffening flange after the sleeve has been applied to the mandrel, said extension adapted to force the mandrel and the sleeve over said roller and then to strip the mandrel therefrom.

NORMAN A. MACK.
